PULSE GENERATOR

Maurice Elie, Paris, France, assignor to Compagnie Générale de Télégraphie Sans Fil, a corporation of France

Application June 20, 1947, Serial No. 755,874
In France September 19, 1939

Section 1, Public Law 690, August 8, 1946
Patent expires September 19, 1959

3 Claims. (Cl. 250—36)

1 This invention relates to arrangements for the production of Synchronized High Frequency Pulses of Trapezoidal Shape. The invention is mainly concerned with magnetron oscillators, but it can also be embodied with the aid of other forms of oscillator having characteristics (to be described later herein) like those of a magnetron.

The invention is illustrated in and explained in connection with the accompanying drawings.

In order that the invention may be the better understood the particular characteristic upon which the operation of the present invention depends will first be described with reference to a magnetron connected in the known circuit of Figure 1.

It is well known that a magnetron comprising one or more anodes and a cathode in an evacuated envelope can produce oscillations in a circuit when it is placed in a suitable magnetic field.

These oscillations can cover an extremely extensive frequency spectrum. The invention is more particularly applicable to the case of very short-waves, but it can also be applied in the whole range of frequencies allowed by these oscillators.

Figure 1 represents diagrammatically a magnetron comprising anodes 1 and a filament 2 in a magnetic field H. Only one anode pair is shown but obviously there may be more. The filament is heated from a source U_f, and the anodes are fed with positive voltage from a source U_p. The anode current I_p is indicated by a milliammeter. The oscillating current, for example, in aerial current loop connected to the anodes, is designated by I_A.

The characteristics of an oscillator as represented in Figure 1 are shown graphically in Figure 2, in which (for a given field strength), the variations of I_p and I_A, are plotted as ordinates against U_p. It will be seen that if the field is kept constant, when the plate voltage U_p increases from zero, the current I_p, which at first is nil, commences at a voltage U, rises slightly, then very abruptly increases to the saturation value I_s, and then remains at that value. The oscillating current I_A starts at the same time as I_p, increases abruptly with it, passes through an extensive maximum, and then progressively decreases down to zero, the fall of current being less steep than the rise.

The property is employed, according to this invention, for the production of synchronised impulses of very high frequency oscillations.

In certain applications, notably in radio detection or so-called radar systems, it is required to

2 transmit impulses of a very high frequency sent out during very short periods at regular intervals. The interval between two pulse emissions is regulated by an alternating synchronisation voltage, the frequency of which is chosen in dependence upon the application in question. The envelope curve for such an emission is required to be of trapezoidal shape, that is to say, that the amplitude of the high frequency oscillations must increase very rapidly from zero up to a certain maximum and then, at the end of the pulse, decrease very rapidly back to zero.

Figure 3 shows one arrangement in accordance with the invention.

Referring to Figure 3, a magnetron 1 has its anode point connected to a source of positive voltage U_p through a resistor 2 and an inductance 3, the latter being shunted by a resistor 4 provided for the purpose of damping self-oscillation in the inductance. The source U_p also feeds the anode of a tube 5 shown as a triode, the control grid thereof being negatively biased through a resistance 6.

This grid receives through a condenser 7, synchronised impulses of the shape shown in Figure 4 (wherein T is the synchronisation period), and produced in any convenient known way. In the arrangement actually shown in Figure 3 a multi-electrode tube, the anode of which is fed with positive voltage through a coil 9, is shunted by a damping resistor 8. The control grid of this tube receives the synchronising voltage through a resistor 13 and a transformer 14. The grid is negatively biased by the action of a resistor 11, in the cathode return path and shunted by a condenser 12. When an alternating voltage of sufficient amplitude is applied to the primary of the transformer 14, voltage impulses of the wave shape shown in Figure 4 appear upon plate of the tube 10. This part of the circuit forms per se no part of this invention.

The control grid of the tube 5 is so biased as to cut off the plate current in the absence of signal input so that positive impulses applied to the said grid cause plate current impulses of similar shape, negative input impulses having no effect.

The plate current impulses produce at the terminals of the coil 3 an induced voltage U the phase of which with reference to the current I is represented graphically in Figure 5.

The voltage applied to the anode point of the magnetron through the resistance 2 is composed as shown in Figure 6 of a continuous feed component U₀ upon which are superimposed alterna-

tions of short duration which follow one another at the frequency of the synchronisation voltage.

In actual practice, transitory phenomena and the effects of self-capacity of the winding somewhat modify the behaviour from that just described, but the foregoing explanation is sufficient for an understanding of the working of the system.

If desired the amplitude of the alternations may be modified by producing reaction in the proper direction between the plate and control grid circuits of the tube 5.

Now, upon reference to the characteristics of the magnetron, it will be seen from Figure 7 that if the variable voltage represented by the curve u (shown in Figure 6) is applied to the magnetron, and the D. C. feed voltage is at a value u_0 lower than, or equal to, the value u at which the magnetron anode current rises, the magnetron will oscillate intermittently for periods each of which corresponds to the application of the positive part of a synchronising-impulse. The duration of each such stable period of oscillation working may be relatively long as compared with the duration of the periods of starting and stopping. The maximum oscillation will be reached with a voltage u_1 and maintained so long as the voltage is between u_1 and u_2 . The envelope of the high frequency impulses will therefore be a double trapezium, as shown in Figure 8, the small base of which is of a width depending on the amplitude of the voltage applied. The plate current envelope curve of the magnetron will also be of trapezoidal form. The sudden setting up of current through the coil 3 tends to give rise to stray oscillations which it is the purpose of the resistance 2 to damp out.

In the absence of oscillations, the plate current and consequently the anode losses are zero. The mean power dissipated is therefore very small as compared with the power applied during an impulse. This is of great advantage because it means that the magnetron is working under much better conditions than if it were working with continuous power applied.

The major part of the voltage applied to the magnetron is supplied by the source of continuous current. This is also an advantage, because the variable portion of the voltage—which portion is only contributory—can be obtained more easily than would be the case if it had to have an amplitude equal to the total peak voltage.

The arrangement shown is, in effect, an amplifier of the positive impulses produced by the tube 10. It will be obvious that such amplification could be dispensed with and that it is possible to apply directly to the magnetron coil 3 impulses of the shape shown in Figure 4 and produced by tube 5, by excitation of its grid through

a transformer such as 14 and a resistor such as 13. In such a case of course the synchronising voltage would have to be of greater amplitude than in the case illustrated.

5 What I claim is:

1. Arrangement for producing trains of oscillations at ultra high frequency comprising, a tube of the magnetron type having an anode, a cathode coaxial therewith, and a magnetic field parallel to the cathode, a source of direct current voltage connected between said cathode and said anode, said direct current voltage being lower than the cut-off and means connected to said anode for superimposing on said direct current voltage impulses at the frequency of said trains and having positive amplitudes such as to carry said anode voltage into saturated current condition and thereby cause the magnetron to oscillate during said impulses with its proper frequency.

2. Arrangement for producing trains of oscillations at ultra high frequency comprising a tube of magnetron type having an anode, a cathode coaxial therewith and a magnetic field parallel with the cathode, a source of direct current voltage connected between said anode and said cathode, said voltage being below that required for current saturation in the tube, a source of sinusoidal oscillations of the frequency of said trains, means for shaping said oscillations into substantially triangular form and for superimposing them upon said direct current voltage so as to carry the magnetron into the saturated current condition during the positive alternations of said impulses and then cause it to oscillate with its proper frequency.

3. Arrangement for introducing trains of oscillations according to claim 2, in which said shaping and superimposing means include an electronic relay fed from said sinusoidal source and having its input circuit negatively biassed, and means for coupling its output circuit to said anode of the magnetron, said coupling means comprising a common shunt inductance in parallel with a resistance.

45 MAURICE ELIE.
